FLUTING MACHINE

William T. Maxant, Ayer, Mass.

Application September 12, 1939, Serial No. 294,559

7 Claims. (Cl. 223—32)

This invention relates to an improvement in fluting machines, and more particularly, to machines for fluting or crimping the edges of ruffled curtains, flounces and dress trimmings, and other fabrics and materials where a crimping or fluting effect is desirable. The machine is of the open-end type, whereby the ruffle or dress trimming can be fluted conveniently without removing it from the curtain or garment to which it is applied.

Fluting machines that have been made and used heretofore have contained numerous disadvantages and objections, particularly in the mounting and the locking of the fluting rollers, which were not capable of ready adjustment or replacement without great inconvenience and without danger of injury to or burning of the hands of the workmen.

The object of this invention is to improve the construction of the fluting machine, to provide a quick-lift for separating the rollers when it is desired to feed the material thereto or remove the material therefrom, controlled by one hand of the operator, without danger of burning; to provide for the adjustment of the tension on the rollers in a simple and effective manner without danger of burning of the hands of the workmen; to simplify and improve the manner of changing the rollers by opening up the top roller support without danger to the workmen, and to provide simple and effective guards for the respective rollers which will protect the same from the material except at the meeting edges of the rollers and which eliminate danger to the hands of the workmen.

In carrying out this object of the invention and to incorporate these principal new features, I have embodied the invention in a preferred form thereof, which is illustrated in the accompanying drawings, in which:

Fig. 1 is a side elevation of my improved fluting machine;

Fig. 2 is a top plan view thereof;

Fig. 3 is a vertical sectional view therethrough on the line 3—3 of Fig. 1;

Fig. 4 is a partial longitudinal sectional view, substantially on the line 4—4 of Fig. 2;

Fig. 5 is a detail vertical section showing the roller mountings; and

Fig. 6 is a detail section through one of the top 50 roller journals.

The machine is provided with a base 1 for supporting the principal parts thereof and which may be secured to a table or other support for the machine where it may be fastened in place 55

for use. The base 1 is constructed to support a pair of fluting rollers at one end portion thereof and drive means for the rollers at the opposite end portion thereof. The top and bottom rollers 5 are designated by the numerals 2 and 3 respectively and have the usual grooved or corrugated peripheral surfaces shaped and constructed to interfit with each other and to form the desired flutes or crimps in material passed therebetween.

10 The bottom roller 3 is mounted in a yoke 4 secured upon one end portion of the base 1. The roller 3 has a journal 5 projecting outwardly from the outer end of said roller, while its inner end has an inwardly extending stub shaft 6 fixed thereto. The journal 5 is mounted in a pair of laterally spaced rolls 7 secured to the inner face of one side of the yoke 4, while the stub shaft 6 is similarly mounted in a pair of rolls 8 secured to the inner face of the opposite side of the yoke 15. 20 The roller 3 and its supporting journals rest freely upon the rolls 7 and 8 so that the roller 3 is capable of ready removal therefrom when it is desired to change the roller to one of a different size or depth of crimp.

25 For supporting the top roller 2, a standard 9 is secured upon the base 1 adjacent the inner ends of the rollers 2 and 3. The standard 9 is preferably of cast metal, such as cast iron or aluminum, and is hollow, terminating at its upper end in an integral laterally extending hollow supporting arm 10 which extends substantially parallel with the top roller 2 beside the same, to a point adjacent the middle of the roller. At its outer end, the supporting arm 10 carries a laterally extending bracket 11, preferably cast integrally therewith or secured thereto and which bracket 11 extends in the opposite direction from the supporting arm 10 from the position of the upper roller 2, as shown in Fig. 3.

30 40 The top roller 2 is carried by a supporting frame 12 which extends longitudinally over the top roller 2 and has downturned opposite ends 13 embracing the ends of the roller. The roller 2 has journals 14 at opposite ends thereof which bear upwardly against a pair of rolls 15 (Fig. 5) for rotary movement, one of the journals 14 being mounted in a bushing 14' in the frame end 13. The journals 14 are held against the rollers 15 by clips 16 which underlie the journals 14, and which clips are detachably secured by screws 17 to the respective downturned ends 13. The fluting roller 2 may be removed from the supporting frame 12 upon removal of the clips 16 which allows the fluting roller to drop out of the frame for ready replacement.

The supporting frame 12 preferably has a frame arm 18 cast integrally therewith and extending laterally therefrom in overlapping relation with the bracket 11, to the outer end of which said frame arm 18 is pivoted at 19 for lateral swinging movement of the supporting frame 12 with the top roller 2 to a raised or inverted position when desired.

For holding the supporting frame 12 at its lower position, as well as for applying tension thereto, I have provided a screw 20 which extends loosely through an orifice 21 in the frame arm 18, and has a hand knob 22 on the upper end thereof. The lower end portion of the screw 20 is threaded at 23 to engage in a threaded orifice in a lug 24 that extends laterally from and is secured upon the end portion of the supporting arm 10. A coiled spring 25 is sleeved upon the screw 20 and is interposed between the knob 22 and the frame arm 18, normally tending to apply spring tension to said arm to force the supporting frame 12 and top roller 2 downward, with said top roller bearing resiliently upon the bottom roller 3.

The frame 12 may swing about the pivot 19 in moving in response to the spring 25, and upon unscrewing the screw 20 from the lug 24, the supporting frame 12 may be lifted back to its retracted position with the rollers separated from each other. Thus one screw connection is provided both to adjust the tension of the top roller and to control the movement of the top roller to its inoperative or retracted position when it is desired to remove or replace the rollers; and this screw connection is located sufficiently remote from the top roller that it is not substantially affected by the heat thereof so as to cause danger of burning of the fingers of the workmen in making the adjustment. To hold the screw 20 against separation from the frame arm 18 when said screw is detached from the lug 24, a washer 26 is sleeved on the screw 20 beneath the arm 18 and is held in place by a cotter pin 27 that passes through a screw 20.

Provision is made for lifting the top roller 2 to separate it from the bottom roller 3, particularly when material is fed therebetween or removed and without the necessity for changing the tension of the spring 25 by removing the screw 20. This is accomplished by what is termed a "quick-lift" of the top roller to raise it slightly from the bottom roller sufficiently for the feed of the material; and this may be done by one hand of the operator while he holds the material with the other hand.

To accomplish this result, I have provided a bell-crank lever 28 housed within the hollow standard 9 and supporting arm 10 and pivoted to the latter at 29. One end portion of the bell-crank lever 28 carries a bearing screw 30 in position to engage a bearing pin 31 slidably received in an orifice 32 in the end portion of the supporting arm 10. The bearing pin 31 projects upwardly from the bearing screw 30 and presses against the under side of the frame arm 18 tending to raise said frame arm when the pin 31 is pushed upwardly and to lift the top roller 2 against the tension of the spring 25, when the bell-crank is moved from its full line position 24 to its dotted line position therein.

The shifting of the bell-crank lever 28 is caused by the engagement of its opposite arm by a bearing lug 33 secured to one side of a shaft 34, as shown in Fig. 4, and which bearing lug is moved into engagement with the arm of the bell-crank lever when the shaft is rotated in a counter-

clockwise direction as indicated in Fig. 4 or in a clockwise direction as shown in Fig. 1. The shaft 34 is journaled in bearings in opposite sides of the standard 9 and extends forwardly therefrom to the front of the machine, as shown in Fig. 2, where it terminates in an upturned lever portion 35 having a hand knob 36 thereon for manipulation by one hand of the operator. Thus, by shifting the lever portion 35 from the right to the left in Fig. 1, the operator may separate the rollers 2 and 3 sufficiently to insert or remove the material therefrom.

To vary the degree to which the rollers may be brought together when the machine is operated, I have provided an adjusting screw 37 (Fig. 4) which extends into the path of the bell-crank lever 28 to limit the extent of movement of said lever when the lever arm 35 is shifted to a closed position. For holding the screw 37 in its adjusted position, a lock nut 38 is provided. Thus when a thick place or seam in the material is reached, the operator may turn down the adjusting screw 37 which will lift the top roller sufficiently to clear the thickness without causing the increased pressure thereon that would result from the movement of the thickened portion between the rollers. This adjusting screw 37 may be used also to accommodate the rollers to different thicknesses of the material by regulating the extent to which the rollers approach each other when the lever arm is moved to its closed position.

The supporting frame 12 is provided with a downturned roller guard 39 cast in one piece therewith and extending substantially throughout the length of the top roller 2 so as to protect the latter effectively from the hands of the operator, against burning or injury thereto.

A guard apron 40 is provided along the bottom roller 3, being supported on brackets 41 secured to the yoke 4. This guard apron 40 is also preferably of cast metal construction, such as cast iron, and terminates in a rounded end portion 42 that extends about the end of the bottom roller 3 and guards the material from the bearings thereof as it passes through the rollers. It will be noted that the machine is open at its outer end for ready passage of the material between the rollers without removal of the crimped edges or ruffles from the curtain or garment, and this guard portion 42 protects the garment or curtain from injury during passage of its edge portion through the machine.

The rollers may be operated by any suitable or desired means but I have shown an electric motor 43 mounted on the base 1 and driving speed reducing gearing in a housing 44 through a belt operating in a guard 45. The speed reducing gearing operates a drive shaft 46 having a detachable clutch engagement with the stub shaft 6, as shown in Fig. 1, for operating the bottom roller 3, which in turn drives the top roller 2 through its interfitting connection therewith.

The top roller 2 is adapted to be heated as by an electric coil designated generally by the numeral 47 in Fig. 3, regulated by a control unit of the usual character, as indicated at 48.

The machine is provided with the usual electrical controls, such as a rheostat for controlling the electric motor 43 so as to adapt said motor to drive the rollers when it is desired to feed material to the machine.

The operation of the machine will be obvious from the foregoing description, but it may be

pointed out that the rollers should be heated first before being put into operation, for which purpose they are moved to their closed position by swinging the lever arm 35 to the left in Fig. 1, and then closing the switch that controls the electric current to the coil 47, which will heat the top roller, and heat will be conducted therefrom to the bottom roller sufficiently for the heating of the latter. Then the rollers may be spaced by swinging the lever arm to the right and they are ready for feeding the material therebetween.

The motor 43 is started, operating the bottom roller and after threading the material in the machine the rollers are again closed and the material is caused to feed through the machine through the operation of the bottom roller and is crimped or fluted according to the shape and depth of the grooves in the rollers. In this way, the operator may control the opening and closing of the rollers by one hand while holding the material with the other and the control lever arm is removed for the source of heat so there is no danger of the burning of the hand of the operator.

The material feeds over the guard apron on the bottom which effectively protects the material from injury by the machine and against getting caught in the roller or its mounting, which is particularly important in the fluting of ruffles of fragile curtain material or the like.

I claim:

1. In a fluting machine, the combination of coacting fluting rollers, a frame carrying one of said fluting rollers and having an arm extending laterally therefrom, a pivotal support for said arm, and means for lifting said frame including a lever extending approximately lengthwise of the rollers and having an operative connection with the arm for swinging the same upward upon actuation of the lever, and a handle structure beside the rollers operatively connected with said lever for actuating the same.

2. In a fluting machine, the combination of coacting fluting rollers, a frame carrying one of said fluting rollers and having a laterally extending arm, means pivotally supporting said arm for upward swinging movement of the last-mentioned roller from engagement with the coacting roller, a bell-crank lever having one arm thereof in operative bearing engagement with the first-mentioned arm for swinging the same upwardly, and a shaft having operative connection with the other arm of said bell-crank lever for actuating the same.

3. In a fluting machine, the combination of coacting fluting rollers, a frame carrying one of said fluting rollers and having a laterally extending arm, a base structure pivotally supporting said arm for upward swinging movement of the last-mentioned roller bodily from engagement with the coacting roller, a pin guided in the base structure and engaging the arm for moving the

same, a bell-crank lever pivoted on the base structure and having one end portion thereof bearing against the pin for moving the same, a shaft having operative bearing engagement with the opposite end portion of the bell-crank lever, said shaft extending transversely of the rollers beside the same, and a handle connected with the shaft for actuating the same.

4. In a fluting machine, the combination of a base structure, coacting fluting rollers, one of said rollers being mounted on the base structure, a frame carrying the other coacting roller, an arm connected with said frame and mounting the same for upward swinging movement, a member operatively connected with said arm and having detachable connection with the base structure normally tending to hold the frame and its roller in operative position, and resilient means connected with said member and bearing against the frame independently of the connection between the member and the arm and normally tending to hold the rollers in coacting engagement.

5. In a fluting machine, the combination of a base structure, coacting fluting rollers, means mounting one of the rollers on the base structure, a frame carrying the other coacting roller and having a laterally extending arm pivotally supported on the base structure, a screw extending through the arm and having detachable engagement with the base structure, and a spring connected with the screw and having bearing engagement with the frame tending to hold the rollers in engagement.

6. In a fluting machine, the combination of a base structure, coacting fluting rollers, means mounting one of said rollers on the base structure, a frame carrying the other coacting roller and having a laterally extending arm connected therewith and pivoted to the base structure, a screw extending through said arm and having detachable engagement with the base structure, and a coiled spring sleeved on said screw and interposed between the head thereof and the frame normally tending to hold the rollers in coacting engagement.

7. In a fluting machine, the combination of coacting fluting rollers, a frame carrying one of said fluting rollers and having an arm extending laterally therefrom, a pivotal support for said arm, means for lifting said frame including a lever extending approximately lengthwise of the rollers and having an operative connection with the arm for swinging the same upward upon actuation of the lever, and a handle structure beside the rollers operatively connected with said lever for actuating the same, and an adjustable stop in the path of movement of the lever for limiting the extent of approach of the frame-supported roller relative to the coacting roller.

WILLIAM T. MAXANT.
